OPHTHALMIC MOUNTING OR THE LIKE

Charles A. Baratelli, Woodstock, Conn., assignor
to American Optical Company, Southbridge,
Mass., a voluntary association of Massachusetts

Application October 13, 1951, Serial No. 16,932

Term of patent 14 years

(Cl. D57—1)

To all whom it may concern:

Be it known that I, Charles A. Baratelli, a citizen of the United States of America, residing at Woodstock, in the county of Windham and State of Connecticut, have invented a new, original, and ornamental Design for an Ophthalmic Mounting or the like, of which the following is a specification, reference being made to the accompanying drawings, forming a part thereof.

Fig. 1 is a front elevational view of an ophthalmic mounting, embodying my new design;

Fig. 2 is a top plan view of the ophthalmic mounting shown in Fig. 1.

The essential features of my design for an ophthalmic mounting are shown in full lines on the drawing, the temples being shown fragmentarily in Fig. 2 for convenience of illustration.

I claim:

The ornamental design for an ophthalmic mounting or the like, substantially as shown and described.

CHARLES A. BARATELLI.
